UNITED STATES PATENT OFFICE.

BENJAMIN F. FORSYTH, OF SALT LAKE CITY, UTAH, ASSIGNOR TO PERFECTION RUG RETAINER COMPANY, OF SALT LAKE CITY, UTAH.

RUG-RETAINER.

1,137,748.

Specification of Letters Patent.

Patented May 4, 1915.

Application filed January 7, 1914. Serial No. 810,892.

To all whom it may concern:

Be it known that I, BENJAMIN F. FORSYTH, a citizen of the United States, residing at Salt Lake City, in the county of Salt Lake and State of Utah, have invented certain new and useful Improvements in Rug Retainers, of which the following is a specification.

It is well known that rugs loosely disposed upon a floor, either bare or on a carpet, have a tendency to roll at the corners and at the edges in such a manner as to become very objectionable, this defect being present more especially in rugs of the smaller sizes.

It is the object of this invention to provide a retainer adapted for attachment on the bottom of the rug to hold the same flat and prevent rolling of the corners and margins, the device of my invention also serving to stretch the rug so as to prevent the same from wrinkling.

It is one of the special objects of my invention to provide a retainer of this character which will not hump or cause any appreciable bulging of the rug at points where it extends over the device of my invention so as to avoid wearing the rug out at those points or places which extend over the retainer.

A further very important feature consists in providing a frame or rug retainer, the parts of which are of a single thickness throughout, in which all portions of the frame are not only uniform in thickness but also lie in a single plane so that no crossed portion or raised portions are embraced within the structure with a resulting thickness.

Other features and objects of the invention will be more fully described in connection with the accompanying drawing and will be more particularly pointed out and ascertained in and by the appended claims.

In the drawing:—Figure 1 is a bottom plan view of a rug showing a retainer attached thereto embodying one form of my invention. Fig. 2 is an enlarged plan view of one portion of the receiver with parts broken away. Fig. 3 is an enlarged plan view of another portion of the retainer with parts broken away. Fig. 4 is a sectional view on line 4—4 of Fig. 1. Fig. 5 illustrates one means of fastening the retainer to the rug.

Like characters of reference designate similar parts throughout the different figures of the drawing.

I have illustrated the device of my invention in connection with one of the small-sized rectangular rugs 1 but the device of my invention is adapted for use with any of the stock sizes, it being understood that there are a limited number of sizes and the device of my invention will be made to accommodate different sizes of rugs so as to avoid the mechanism necessary in employing adjusting devices.

The retainer embodying my invention comprises a central member 2 which extends centrally of the rug and which is provided with forked ends 3, 4, 5 and 6 extending annularly to the central section 2 toward the corners of the rug.

The terminals of the forked ends, as shown in Fig. 1, are insertable in pockets 8, the margins 9 of which are adapted to be sewed or otherwise secured to the rug in a manner to dispose the open ends of the pockets in the position shown, namely, facing inwardly from the margins of the rug. The retainer frame is made of resilient sheet material, which may be sheet steel, and the normal length of the retainer is such that it is necessary to flex or bow the same in order to insert the terminals of the forked ends into the pocket 9, recoil of the frame thereafter being sufficient to straighten the frame and cause the same to engage the outer ends of the pocket with such tension as to not only retain the rug in a flat position but also to stretch the rug both as regards its length and width, the diverging forked ends being positioned or disposed in a manner to most effectively function so as to achieve this object. Of course the pockets 8 will be carefully and accurately sewed or secured to the rug in such a position as to carry out this feature of the invention.

The fastening devices may comprise collapsible stud and socket elements, as shown in Fig. 5, the stud elements 10 being shown secured to the terminals of the forks and the sockets 11 to the bottom of the rug, it being understood that I do not wish to be limited to either of the forms shown, or in any other respect, except to fastening devices which will secure the terminals of the forked ends.

In order to avoid scratching a polished

floor, when a rug provided with my retainer is disposed thereon, I may cover the lower side of the retainer frame with cloth, rubber, or any suitable material, as indicated 5 at 12.

It is one of the features of my invention to provide a retainer frame of a single thickness throughout, or in other words, wherein 10 all portions of the frame are not only uniform in thickness but also lie in a single plane so that there will be no double thickness resulting from one portion of the frame crossing over the other.

I have illustrated in Figs. 2 and 3 one 15 manner of forming a frame of this construction, and as illustrated, the fork end 4 is integral with the central section 2 and is bent outwardly at the desired angle therefrom, the fork 3 is shown welded or otherwise 20 integrally secured to section 2 at the juncture thereof with the fork end 4, as indicated at 13. At the other end of central section 2, I may weld or otherwise integrally attach fork ends 5 and 6 and it will 25 be understood that the juncture of the forked ends with the central section 2, at each end of the latter, will be flush and that there will be no additional thickness and that the forked ends and the central section 30 2 will all lie in a single plane.

In Fig. 4, the thickness of the material 35 has been greatly exaggerated for purposes of illustration but the device of my invention, in practice, lies so flat abreast of the bottom of the rug that no appreciable projection is present on the walking surface, and in cases where the device of my invention is applied to a rug of considerable thickness, no sensation is felt in walking 40 across the rug that would indicate that a frame was below the same.

While I have suggested that the frame 45 may be made of sheet steel, many other sheet materials are available which present the desired flexibility and resiliency to enable the device of my invention to perform its function.

While I have herein shown and described one specific form of my invention, I do not 50 wish to be limited thereto except for such limitations as the claims may import.

I claim:

1. A retainer adapted for use with a rug comprising a resilient retaining frame comprising a single member of flexible sheet material extending centrally along the bottom of the rug throughout the major portion of the length of the frame and including forked ends extending toward the corners, 60 and devices for securing the terminals of the

forked ends to the corner portions of the rug.

2. A retainer adapted for use with a rug comprising a resilient retaining frame of flexible sheet material comprising a central 65 bar adapted to extend longitudinally of the rug and provided with forked ends formed as a part thereof, and devices for securing the terminals of the forked ends to corner portions of the rug. 70

3. A retainer adapted for use with a rug comprising a resilient retaining frame of flexible sheet material extending centrally along the rug and having forked ends extending toward the corners, and devices for 75 securing the terminals of the forked ends to the corner portions of the rug, said rug devices being located on the rug in such spaced relation with respect to the length of the frame as to necessitate bowing or 80 flexure of the frame to effect attachment whereby resulting recoil will cause the frame to stretch the rug both laterally and longitudinally. 85

4. A retainer adapted for use with a rug comprising a retaining frame therefor comprising a central portion constructed to extend longitudinally of the rug having forked ends, disposed at an angle from the extremities thereof to extend toward the 90 corners of the rug and to be connected therewith, the central portion and the forked ends all having the same thickness and all portions of the frame lying in the same plane. 95

5. A retainer adapted for use with a rug comprising an elongated retaining frame therefor, comprising a single member of flexible material formed to have ends extending into proximity to the corners of the 100 rug, and devices for securing the ends of said frame to the rug to hold the frame under compression in the direction of its length.

6. A retainer adapted for use with a rug comprising a frame comprising a single flexible sheet member formed to have angularly disposed ends which extend to points adjacent the corners of the rug, and devices for securing said portions to the rug to place 110 the frame under compression in the direction of its length and stretch the rug longitudinally and laterally.

In testimony whereof I affix my signature in presence of two witnesses.

BENJAMIN F. FORSYTH.
